UNITED STATES PATENT OFFICE.

FERDINAND GERHARD, OF KONIGSBERG, AND ERNST SCHUMACHER, OF FRANKFORT-ON-THE-MAIN, GERMANY.

PRODUCER WITH COOLING WATER JACKET.

Application filed July 9, 1924, Serial No. 725,068, and in Germany September 15, 1921.

This invention relates to a producer with a cooling water jacket. In producers the cooling water jacket is exposed to strong wear as it is submitted from the inside to the action of the air-containing cooling water and from the outside to the erosive actions of coke and slag dust. Consequently leakages occur frequently which give cause for wearisome disturbances of service. As the repairing of a defective cooling water jacket is difficult and requires much time owing to the commonly used form of construction of such cooling water jackets the entire cooling water jacket has to be exchanged after a short time of service, which is rather expensive and the more so as the producer has to be stopped for a long time.

According to this invention the above-mentioned inconveniences are avoided by constructing the cooling jacket of interchangeable, exchangeable water cooled boxes independent of one another, said boxes being of substantially trapezoidal cross section and arranged to form a complete cooling jacket. The several boxes are constructed so that they are shut off from one another; they have each a separate inlet and outlet for the cooling water connected with the main pipes so that they can be easily disconnected from the same. The cooling jacket segments can for instance consist of cast bodies with serpentine cooling channels. The exchangeability can be facilitated by the use of wedge pieces inserted from the inside and serving for securely holding the boxes in position. These wedge pieces are pressed against the adjacent elements of the cooling jacket by means of screw bolts accessible from the outside.

If for each segment a separate outflow for the cooling water is provided, which freely terminates into an open discharge conduit, it is possible to determine at every moment whether the circulation of the cooling water is normal, so that disturbances in the supply of cooling water or leakage from individual segments can be found out soon enough to prevent serious damages.

Several embodiments of the invention are shown by way of example in the accompanying drawing, in which:

Fig. 1 shows one form of construction in vertical longitudinal section, the section being taken on the line 1—1 of Fig. 2.

Fig. 2 is a horizontal cross section on the line 11—11 of Fig. 1.

Figs. 3 and 4 are vertical and horizontal sections respectively representing a second form of construction, the sections being taken on the lines indicated.

According to Figs. 1 and 2, the producer comprises a permanent outer wall consisting of an outer envelope *c* and an inner layer of insulating material *p*, and a cooling jacket composed of water boxes *k* which are secured in position by means of wedge pieces *l* inserted from the inside and adapted to be pulled in between two adjacent water boxes *k* through the action of screw bolts *m* projecting through the outer envelope *c*.

The cooling water is supplied to the water boxes *k* from an annular pipe *d* with which the water boxes are connected by tubular connecting pieces *g* of which each one has a valve *f*. The water flows out from the water boxes *k* through pipes *h* into an open conduit *i*.

In the second form of construction shown in Figs. 3 and 4, respectively, the cooling jacket is composed of the cast elements *n* having each a serpentine cooling channel *o*. The elements *n* are wedged apart and pressed against the permanent outer wall of the producer by means of wedge pieces *l* and screw bolts *m*. Water is admitted from annular pipe *d* through valves *f* and pipes *g* to the lower ends of channels *o* through which it passes upwardly and out through pipes *h* into open conduit *i*.

In both forms of construction the cooling elements are of such breadth that they can be easily inserted through a sight hole (not shown) in the top of the furnace.

We claim:

In a furnace having a permanent outer wall, a cooling water jacket forming the in-

ner lining of the furnace comprising independent segments, means for conducting water through said segments, the adjacent edges of the segments diverging toward the 5 interior of the furnace, wedge shaped members interposed between said diverging edges, and means for drawing said wedge shaped members toward said permanent

outer wall to clamp said segments to said wall.

The foregoing specification signed at Frankfort-on-Main, Germany, this 12th day of June, 1924.

FERDINAND GERHARD.
ERNST SCHUMACHER.
